US00D990204S

(12) **United States Design Patent** (10) **Patent No.:** **US D990,204 S**
(45) **Date of Patent:** **** Jun. 27, 2023**

(54) **PRODUCT DISPLAY UNIT**

- (71) Applicant: **Marmon Foodservice Technologies, Inc.**, Osseo, MN (US)
- (72) Inventors: **Daniel Gatto**, Brooklyn, NY (US); **Jonathan Andrew Hughes**, Wyndmoor, PA (US); **Douglas E. Best**, Long Beach, NY (US)
- (73) Assignee: **Marmon Foodservice Technologies, Inc.**, Osseo, MN (US)
- (**) Term: **15 Years**
- (21) Appl. No.: **29/828,845**
- (22) Filed: **Mar. 1, 2022**

Related U.S. Application Data

- (62) Division of application No. 29/712,534, filed on Nov. 8, 2019, now Pat. No. Des. 952,381.
- (51) **LOC (14) Cl.** **06-06**
- (52) **U.S. Cl.** **USPC D6/702; D6/672**
- (58) **Field of Classification Search**
USPC **D6/672, 702, 703, 703.1, 705, 705.1, D6/705.5, 512, 513, 515**
CPC **A47F 1/00; A47F 1/04; A47F 1/12; A47F 1/125**
- See application file for complete search history.

Primary Examiner — Steven J Czyz

(74) *Attorney, Agent, or Firm* — Andrus Intellectual Property Law, LLP

(57) **CLAIM**

The ornamental design for a product display unit, as shown and described.

DESCRIPTION

FIG. 1 is a top front right side perspective view of a product display unit;

FIG. 2 is a bottom front left side perspective view thereof;

FIG. 3 is a top rear left side perspective view thereof;

FIG. 4 is a top rear right side perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The dash-dot-dash broken lines represent the boundaries of the claimed design and form no part of the claimed design. The broken lines outside of the boundaries represent portions of the product display unit that form no part of the claimed design.

1 Claim, 9 Drawing Sheets
